ELECTRIC ARC MELTING FURNACE

Gustav Adolf Sixel, Dusseldorf-Kaiserswerth, Germany, assignor to Aktiengesellschaft fuer Unternehmungen der Eisen- und Stahlindustrie, Essen, Germany

Application April 15, 1957, Serial No. 652,955

Claims priority, application Germany May 9, 1956

8 Claims. (Cl. 13—10)

Electric arc melting furnaces, as they are commonly used in the production of steel, employ electrodes operating at low voltages so that they have to be connected to the high power lines via a transformer. In case of larger furnace units, the current densities become very high. This makes it difficult to provide low-loss connections of the necessary flexible conductors between the transformer and the terminals of the electrodes.

These known melting furnaces must be made movable to permit discharging of the molten metal or charging of the scrap metal. However, in the past, the associated transformers have not taken part in the furnace movements, said transformers being separate and stationary with respect to the adjacent furnaces. The positions of the connection terminals of the electrodes are considerably displaced during furnace movement with respect to the connections at the stationary transformers when the furnace is moved, as indicated in the foregoing. As a result of this, relatively long connecting conductors have to be provided between the electrode and transformer terminals. Such long connecting conductors, which are mostly of copper, tend to sag to a great extent and are, therefore, very inconvenient and tend to have great current losses.

In order to decrease the length of these conductors, electric arc melting furnaces have been designed in such a manner, that the electrodes and thus their terminals do not take part in the displacements of the furnaces, for example, in the tilting movements. However, even in such construction, the minimum electrical length of the conductors necessary for connecting the transformer to the electrode terminals would be too short to permit the furnace cover to be removed or turned by means of its carrying frame when recharging the furnace with scrap metal. During such operations, the conductor connections at the transformer and those at the electrode terminals are moved away from one another, so that greater conductor lengths become necessary.

It is a primary object of the present invention to avoid long connecting conductors such as have been heretofore necessary to permit turning or removing of the furnace cover during the recharging.

It is another object of the invention to place the transformer on the furnace cover supporting frame which includes the electrodes, so that the transformer takes part in all turning or displacing movements of the cover supporting frame. As a result of such structure, the connecting conductors between transformer and electrode terminals can be made of minimum length, so that these conductors scarcely sag and are short enough to have low electrical losses and satisfactory mechanical stability.

It is a further object of the present invention to pass the feed lines from the high voltage power lines to the primary of the transformer through a hollow pivot about which the cover supporting frame is rotatably mounted.

Still further objects and the entire scope of applicability of the present invention will become apparent from the

detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

In the drawings:

Figure 1 is a side elevation of an electric arc furnace and associated transformer according to the invention;

Figure 2 is a plan view of the electric arc furnace and transformer of Figure 1, but with the furnace cover shown in displaced position for recharging;

Figures 3 and 4 show partial vertical enlarged sections taken in two planes perpendicular with respect to one another and passing through a modified cover supporting frame at its pivot, according to an object of the present invention, and wherein Figure 3 is a section taken along line III—III of Figure 4 and looking in the direction of the arrows.

Referring in more detail to the drawings, Figure 1 shows a furnace body *a* open at the top and mounted on rocking cradles *b* in a manner known per se. Electrodes *c*₁, *c*₂ and *c*₃, carrying terminals *d*₁, *d*₂ and *d*₃, respectively, are mounted in and passed through a cover *g* seated on the open top of the furnace body *a*.

A cover supporting frame *e* carries the cover *g* with the electrodes *c*₁, *c*₂ and *c*₃ and their clamps or terminals *d*₁, *d*₂ and *d*₃, i. e., this cover *g* is suspended from an upper arm *e*₁ of the frame *e* overlying the cover *g* by means of cables indicated at *f*₁ and *f*₂. When the furnace is to be charged, sectors *f*₁' and *f*₂' to which these cables at *f*₁ and *f*₂ are respectively attached will lift the cover *g* when the sectors *f*₁' and *f*₂' are turned in the direction of the arrows by means of a drive mechanism (not shown). The supporting frame *e* rests on rollers *h* running on a stationary track *i* disposed in a circular arc. The supporting frame *e* rotates about a fixed pivot *k*, about which this frame *e* can be turned or swung to the position shown in Figure 2 by means of a drive mechanism *l*.

A transformer *m* is mounted on a platform *e*₂ of the cover supporting frame *e* and the secondary of this transformer is connected to the terminals *d*₁, *d*₂ and *d*₃ of the electrodes *c*₁, *c*₂ and *c*₃ by means of conductors *n*₁, *n*₂ and *n*₃. The terminals of the primary of the transformer *m* are connected to the high voltage power lines (not shown) by means of lines or bus bars *x*, *y*, *z*.

In order to permit limited displacement of the feed lines to the primary of the transform *m* from the power lines during the turning of the frame *e*, these feed lines are passed through a hollow pivot *k*', as shown in the modified embodiment of Figures 3 and 4. The part of the feed lines passing through the hollow pivot *k*' which is mounted on the floor by means of a foot *k*'₁ constitutes the end portion of a high voltage cable *q* connected to the supply power lines (not shown). This cable *q* enters the hollow pivot *k*' from an underground duct *r* through which the cable *q* is passed. The cable *q* ends in a cable head *t* just outside and above the top of the pivot *k*', from which the three phases emerge as bare conductors *x*, *y* and *z*. Insulators *p*₁, *p*₂ and *p*₃ mounted above the upper end of the hollow pivot *k*' by means of a bracket *o* support the bare conductors *x*, *y* and *z* close to their ends where they emerge from the cable head *t*. Two spaced sets of insulators *u*₁, *u*₂ and *u*₃ and *u*'₁, *u*'₂ and *u*'₃, secured to a bracket or vertical extension *w* of the carrying frame *e* at the right side thereof, serve as further spacers for the bare conductors *x*, *y* and *z*, ending at the high voltage terminals on top of the transformer *m* (see Figure 1). Since the insulators *u*₁, *u*₂, *u*₃, *u*'₁, *u*'₂ and *u*'₃ are subjected to a turning movement of about

30° of the frame *e*, portions *v*₁, *v*₂, *v*₃ of the conductors *x*, *y* and *z* between the insulators *p*₁, *p*₂ and *p*₃ and the insulators *u*₁, *u*₂, *u*₃ have to be made flexible to permit the necessary displacements.

In certain types of furnaces, the frame *e* may be displaced linearly rather than rotationally and, in such case, may be designed in the form of a gantry. However, the construction illustrated in Figures 1 and 2 of the drawing has the advantage that the access to the furnace is cluttered only at one side thereof by the cover supporting frame.

I claim:

1. An arc melting furnace supplied with electrical energy from a power line, comprising a melting vessel open at its top, a cover removably seated on said top, at least one electrode mounted in said cover, a cover-supporting frame carrying said cover and said associated electrode when said cover is unseated from said top, means to displace said supporting frame with respect to said melting vessel to uncover the latter, a power transformer supplying the electric energy and having a primary connected to said power line, said transformer being mounted on said supporting frame, and electric conductor means connected between the secondary of said transformer and said electrode.

2. An electric arc melting furnace according to claim 1, wherein a stationary pivot is provided and wherein said supporting frame is rotatably journaled on said pivot to permit turning movements of said frame with respect to said melting vessel.

3. An electric arc melting furnace according to claim 1, wherein said cover is suspended from said supporting frame by means of flexible members adapted to lift said cover from said melting vessel.
5. An electric arc melting furnace according to claim 3, wherein said supporting frame has an arm overlying said cover, said flexible members being suspended from said arm.
- 10 6. An electric arc melting furnace according to claim 1, wherein said supporting frame has a platform on which said transformer is mounted.
- 15 7. An electric arc melting furnace according to claim 6, wherein a stationary track in an arc about the axis of said pivot is provided and wherein rollers are rotatably mounted on the bottom of said supporting frame to roll on said track, said platform being disposed between said track and said rollers.
- 20 8. An electric arc melting furnace according to claim 2, wherein said pivot is hollow and the feed lines to said primary of said transformer are passed through said pivot.

UNITED STATES PATENT OFFICE
CERTIFICATE OF CORRECTION

Patent No. 2,852,585

September 16, 1958

Gustav Adolf Sixel

It is hereby certified that error appears in the above numbered patent requiring correction and that the said Letters Patent should read as corrected below.

In the grant, lines 2 and 12, and in the heading to the printed specification, line 4, for "Unternehmung" read -- Unternehmungen --; in each occurrence.

Signed and sealed this 13th day of January 1959.
